UNITED STATES PATENT OFFICE.

HUBERT HEBERT, OF LAKE LINDEN, MICHIGAN.

SPRING-BED.

SPECIFICATION forming part of Letters Patent No. 242,313, dated May 31, 1881.

Application filed April 7, 1881. (Model.)

To all whom it may concern:

Be it known that I, HUBERT HEBERT, of Lake Linden, in the county of Houghton and State of Michigan, have invented a new and 5 Improved Spring-Bed, of which the following is a full, clear, and exact description.

The invention consists in a spring-bed formed of a series of slats resting on crossed inclined spring-slats, the outer lower ends of which are 10 fastened to the longitudinal side bars of a base-frame, whereas the middle of these spring-slats is supported by two adjustable longitudinal rails passing through the middle of the base-frame, by means of which middle rails the 15 elasticity of the spring-slats can be adjusted.

In the accompanying drawings, Figure 1 is a plan view of my improved spring-bed, showing some of the upper slats and some of the spring-slats removed. Fig. 2 is a cross-sectional elevation of the same on the line $x-x$, Fig. 1. Fig. 3 is a longitudinal sectional elevation of the same on the line $y-y$, Fig. 2.

Similar letters of reference indicate corresponding parts.

25 The slats A are provided with short longitudinal slots B at the ends, and through these slots screws or rivets C pass into the ends of crossed spring-slats D, the lower ends of which are fastened to the longitudinal rails E of a base-frame, F, these spring-slats D passing 30 from one end of the slats A to the opposite

longitudinal rail E of the base-frame. The spring-slats D rest, near the center, on the longitudinal rails G, having their upper surfaces beveled toward the ends of the base-frame and 35 passing through the middle of this base-frame. These central longitudinal rails G are secured on the transverse end rails H of the base-frame by strips J and screws L, and are provided on their upper surfaces with blocks K 40 for separating the spring-slats D from each other and keeping them in place. The middle longitudinal rails, G, are adjustable, and if they are separated the elasticity of the spring-slats is decreased, whereas if they are brought 45 together the elasticity of these slats is increased, their inclination varying accordingly.

The slats A and the spring-slats D are preferably made of wood, but may be made of metal.

Having thus described my invention, I claim 50 as new and desire to secure by Letters Patent—

In a spring-bed, the combination, with the slats A, of the spring-slats D, the base-frame 55 F, the adjustable rails G, G, and the strips J, substantially as herein shown and described, and for the purpose set forth.

HUBERT HEBERT.
